UNITED STATES PATENT OFFICE.

IRA W. GLAZIER, OF MILLBURY, MASSACHUSETTS, ASSIGNOR OF ONE-HALF
TO CHARLES OLMSTED THOMPSON, OF NEW YORK, N. Y.

TENSION DEVICE FOR SEWING-MACHINES.

SPECIFICATION forming part of Letters Patent No. 270,188, dated January 2, 1883.

Application filed October 31, 1882. (No model.)

To all whom it may concern:

Be it known that I, IRA W. GLAZIER, a citizen of the United States, and residing at Millbury, in the county of Worcester and State of Massachusetts, have invented new and useful Improvements in Tension Devices for Sewing-Machine Spools, of which the following is a specification.

My invention consists of a regulator in combination with the flier-guide, by which the thread is led off from the spool on the spindle whereon the said flier-guide swings, and by its *vis inertiae* compensates for the irregularities of tension by overrunning the flier-guide when it slacks by increased resistance of the unwinding thread, and falling back when the speed of the flier-guide is accelerated by diminished resistance, all as hereinafter fully described, reference being made to the accompanying drawings, in which—

Figure 1 represents in perspective view a large commercial spool such as is employed for delivering thread to sewing-machines used in manufacturing establishments, together with the ordinary flier-guide for taking off the thread, with my improved regulator applied thereto. Fig. 2 is a perspective of a detail of the device.

I arrange the spool *a* on a vertical spindle, *b*, fixed in any suitable base, and extending up a suitable distance through the top of the spool, and mount the flier-guide *c* thereon, said guide being formed on the lower end of the vertical arm *d*, turned downward along the side of the spool from the horizontal arm *e*, extending over the top of the spool to the spindle, and connected therewith by the coil *f*, suitably for revolving freely on the spindle by the effect of the thread as it is rapidly drawn off from the spool by the machine to which it passes in any desired direction after leaving the stationary guide *g*.

I make a guide, *h*, at the angle between the arms *d* and *e* and directly over the guide *c*, in order that the thread may be led from said guide *c*, so as not in any case to have contact with the head of the spool in case it runs slack, to prevent it from being caught thereon by any roughness of the surface, which sometimes ex-

ists to such extent as to materially interfere with the proper delivery of the thread.

Over the flier-guide *c*, I mount the regulator-guide *j* of my invention, which is formed on the end of an arm, *k*, projecting from a coil, *l*, by which said arm is mounted on the spindle *b* above the coil *f*, and with an intervening washer, *m*, to prevent any conflict of the respective coils, and through this guide I pass the thread from guide *c* to *g*, preferably passing it also through guide *h*; but said guide *h* may be omitted, if preferred, although I find it very useful for the purpose above stated.

It will be readily seen that the *vis inertiae* of the guide *j* will largely counteract the irregularities in the tension of the thread caused by the varying resistance of the unwinding, due to the differences of the adhesion of the threads in different parts of the spool by the overwinding of some coils of thread on others, and by other conditions.

While I prefer to make arms *k* and *e* independently of each other, they may be connected by connecting the coils *f* *l*, or by making the whole in one piece of wire, the spring of the coil being depended on for the compensating action of the guide *j*, said coil being made sufficiently light for the purpose, and the guide *j* being made heavier, if desired; but the range of the regulator will not be as great as when the said guide is made separately from guide *c*, as here shown. In practice the guide *c* will be extended less than half the length of the spool from the top downward, because its function is mainly to guide the thread downward from near the top of the spool, so as to clear the head of the spool. From the lower portion of the spool the thread runs upward more naturally and with less obstruction than it runs from the upper part downward, thereby making a better contrivance by locating guide *c* well up near the top of the spool.

It will be seen that in case the guide *c* should by its momentum overrun guide *j* by reason of any sudden slackening of the tension the slack will be taken up by the guide *j* following behind, and should guide *c* fall back by greater tension the momentum of guide *j* will be added to that of guide *c*, to facilitate the detach-

ment of the thread from the spool. Generally the two guides will run together—that is to say, so that the line of the thread will be straight, or thereabout, from guide *h* to *g* when the tension is uniform.

It will also be seen that the guide *c* being located near the top of the spool will prevent the thread from falling over and getting under the lower spool-head when the machine stops and the thread slackens, which occurs when the guide runs too low or when a gravity-guide drops to its lower position.

For the purpose of connecting all the parts of the tension device together to enable them to be more readily taken off and put on the spindle when the spools are changed, I propose to employ a tube, *b'*, with washer *n* attached near the lower end, on which coil *f* rests, and having washer *m* fitted loosely on it for the coil *l* to rest on, and also having a cap, *o*, at the top, which may be permanently or detachably connected as preferred, said tube being fitted to be readily put on and taken off the spindle.

Having thus described my invention, what I claim, and desire to secure by Letters Patent, is—

1. The combination, in a thread-tension de-

vice for sewing-machine spools, of the regulator-guide *j* with the flier-guide *c*, spool *a*, and the guide *g*, substantially as described.

2. The combination, in a thread-tension device for sewing-machine spools, of the regulator-guide *j* with the flier-guides *c* and *h*, spool *a*, and the guide *g*, substantially as described.

3. The combination, in a thread-tension device for sewing-machine spools, of the regulator-guide *j* and flier-guide *c*, said guides being mounted on the spindle *b* by coils *f* and *l*, substantially as described.

4. The combination of the connecting-tube *b'*, washers *m n*, and cap *o* with the guides *c j* and the spindle *b*, substantially as described.

5. The guides *c* and *j*, mounted on a connecting-tube, *b'*, substantially as set forth, in combination with spindle *b* and spool *a*, substantially as described.

In witness whereof I have hereunto signed my name in the presence of two subscribing witnesses.

I. W. GLAZIER.
